RING BENDING MECHANISM

George C. Minister, Columbus, Ohio, assignor to
The Josten Manufacturing Co., Owatonna,
Minn., a corporation of Minnesota

Application June 7, 1937, Serial No. 146,757

1 Claim. (Cl. 153—46)

The invention relates to finger ring bending mechanisms and more particularly to a mechanism of this type adapted to shape a generally straight elongated ring blank into annular form.

5 One object of the present invention is to provide an improved mechanism of the type set forth which is simple and rugged in construction and which is easy to operate.

A more specific object of the invention is to 10 provide such a mechanism which is especially adapted to bend ring blanks for signet rings into annular shape with a true circular inner surface despite irregularities in the thickness and surface contour of the ring.

15 Further objects and advantages of the invention will become apparent as the following description proceeds and the features of novelty which characterize the invention are pointed out with particularity in the claim annexed to and 20 forming a part of this specification.

For a better understanding of the invention, reference may be had to the accompanying drawing in which

25 Figure 1 is a perspective view of a ring bending mechanism embodying the invention.

Fig. 2 is a longitudinal sectional view of the mechanism shown in Fig. 1.

30 Figs. 3 and 4 are respectively perspective and longitudinal sectional views of a ring blank adapted to be operated upon by the mechanism shown in Figs. 1 and 2.

35 Figs. 5, 6 and 7 are fragmentary horizontal plan views of a portion of the bending mechanism shown in Figs. 1 and 2 illustrating successive steps in the operations performed on a ring blank such as that shown in Figs. 3 and 4.

For purposes of illustration, the invention has 40 been shown herein as embodied in a mechanism particularly adapted for bending finger ring blanks of the type disclosed in my Patent No. 2,035,562, issued March 31, 1936, but it will be understood that the present invention is also applicable to the bending of other types of ring blanks. The bending mechanism includes in 45 general a cylindrical forming member or anvil 10 about which the ring blank is bent, a relatively movable clamping member 11 adapted to clamp the blank in position against the cylinder 10, and a smoothing member 12 operable to bend 50 the laterally extending portions of the clamped blank about the cylinder, all of these parts being carried by a base 13.

In the particular construction illustrated, the cylindrical forming member 10 is shown as carried by an axially extending pin 14 inserted in a

bore 15 in the base 13 and detachably held in position therein by a set screw 16. The forming member may thus be readily detached from the base and a forming member of different diameter substituted so that rings of any selected diameter 5 may be fashioned with the mechanism shown.

In order to clamp the ring blank firmly in position against the side of the forming member 10, the clamping member 11 is provided with a broad substantially rectangular plate or shoe 17 secured to the end of a plunger 18 mounted for longitudinal sliding movement on the base 13 in a guide member 19. Reciprocation of the plunger 18 is effected by a cam 20 peripherally engageable with the butt of the plunger 18 and pivotally mounted on an eccentrically located pin 21 threaded in the base 13. Rotation of the cam 20 is had by a manual operating handle 22. A tension spring 23 secured at its opposite ends to pins 24 and 25, fixed respectively on the plunger 18 20 and pivot 21, serves to maintain the plunger in engagement with the cam so that the plunger is projected and retracted in accordance with the rotation of the actuating cam.

The smoothing member 12 has been illustrated 25 in the form of a roller mounted for swinging movement about the axis of the cylinder 10 as well as for bodily movement toward and away from the same. Thus, the roller 12 is rotatably mounted on a pin 26 journaled in the bifurcated 30 forward end of a supporting member 27 slidably mounted for longitudinal movement on a swinging arm 28 by screws 29 passing through elongated guide slots 30. The arm 28 is detachably mounted on an axial boss 31 on the upper end 35 of the forming cylinder 10 for swinging movement about the same.

Axial movement of the supporting member 27 and its attached smoothing roller 12 is preferably effected by a manually operated screw mechanism in order that the operator may readily determine the pressure required in the manipulation of the mechanism. In the device illustrated, the roller 12 is shifted bodily toward 45 and away from the axis of the forming cylinder 10 by rotation of a screw 32 having a manual operating handle 33 and threaded in the swinging arm 28, the inner end of the screw being splined to the supporting member 27 as indicated at 33 (Fig. 2).

A signet ring blank 34 of the type referred to above has been shown in Figs. 3 and 4. This blank includes an outer member 35 having a recessed lower side and an inner lining member 55

36. The central portion 37 of the blank is recessed inwardly as indicated at 38.

As the first step in fashioning the blank 34 into the desired annular shape, the outer surface of the depressed or recessed portion 38 is bent flat. To this end, the blank is positioned between the forming cylinder 10 and clamping plate 17 (Fig. 5) whereupon the plunger 18 is moved axially toward the forming cylinder, thus flattening the recessed central portion of the blank and causing the laterally extending portions 39 of the blank to be bent at an angle with respect to the center portion (Fig. 6). This displacement of the lateral ends of the blank, together with the tapered contour of the nose of the housing 19, permits the smoothing roller 12 to be positioned, as shown in Fig. 6, against one of the shanks of the ring blank. The operator moves the smoothing roller 12 into firm engagement with the blank by rotating the screw 32 and subsequently swings the arm 28 and its attached roller 12 about the axis of the forming cylinder 10 in the direction of the arrow 40 (Fig. 6), thus bending the laterally extending portion 39 of the ring blank about the cylinder into the configuration shown in Fig. 7. In the course of this bending operation the operator moves the roller 12 toward the axis of the forming member 10 as the thickness of the blank decreases so that a uniform bending pressure is applied to the ring blank. Subsequently, the second laterally extending portion of the blank is bent about the forming cylinder 10 in a like manner. The blank may then be removed from the forming cylinder and the abutting ends soldered or otherwise secured together.

Although a particular embodiment of the invention has been shown and described in some detail for purposes of illustration, there is no intention to thereby limit the invention to such embodiment but, on the other hand, the appended claim is intended to cover all modifications within the spirit and scope of the invention. 5

I claim as my invention:

In a mechanism for forming finger rings from 10 elongated generally straight blanks, the combination of, a base, a forming cylinder on said base of a diameter equal to the desired interior diameter for the finished ring, a clamping member mounted for axial sliding movement on said base toward and away from said cylinder to clamp the central portion of the blank therebetween, means including a peripheral cam pivoted on said base adjacent the outer end of said clamping member for moving the same into and out of clamping position with respect to said cylinder in response to oscillation of said cam, said last named means including means for urging said outer end of said axial sliding clamping member into abutment with the periphery of said oscillatable cam, means including a roller arranged for swinging movement about the axis of said cylinder for progressively pressing the laterally extending portions of the clamped blank 20 against the cylinder in ring shape, and means including a screw member for moving said roller toward and away from said axis. 25
